UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

TELEPHONE SUBSTATION SET.

Application filed October 8, 1917. Serial No. 195,364.

To all whom it may concern:

Be it known that I, KENNETH S. JOHNSON, a citizen of the United States, residing at Jersey City, in the county of Hudson and State of New Jersey, have invented certain new and useful Improvements in Telephone Substation Sets, of which the following is a full, clear, concise, and exact description.

This invention relates to telephone substation sets and in particular to so arranging and proportioning the elements of a telephone substation local battery set, which consists of a receiver, transmitter and a transformer, that the set will be of maximum theoretical efficiency for two-way signaling efficiency irrespective of what values are assigned to the resistance of the transmitter, the set impedance and the receiver impedance. By maximum efficiency in a two-way signaling system as exemplified in a telephone substation is meant the condition wherein, assuming reactances to act as pure resistances, in receiving, fifty per cent of the energy received in the substation is delivered to the receiver, and, in transmitting, fifty per cent of the energy generated in the transmitter is delivered to the line. A full discussion of two-way signaling efficiency in telephone substations will be found in the patent of George A. Campbell, No. 1,254,474, dated January 22, 1918. A particular object is the fulfilment of the above conditions where the value assigned to the set impedance is large.

These objects are attained in substations of the form diagrammatically shown in the accompanying drawings, wherein Fig. 1 illustrates one embodiment of the invention; and Fig. 2 illustrates a variant but fundamentally equivalent form. The form of Fig. 1 would be assumed by the circuit of Fig. 2 in case certain conditions were imposed upon the elements of the substation as hereinafter set forth. Fig. 1^a shows one different possible location for the local battery. Fig. 1^b shows another possible location for the battery in case a permanent magnet receiver is used. Fig. 2^a shows a variation of the circuit of Fig. 2.

Referring specifically to Fig. 1, numerals 1, 2 and 3 represent three coils or portions of the winding of an auto-transformer. Around portion 1 is connected a transmitter

4, around portions 1 and 2 is connected a line 6, and around portions 1, 2 and 3 is connected the receiver 5. The windings of the coil are so arranged that currents passing, as shown by the arrows, produce a series aiding effect in the transformer as a whole. Battery 7 is placed in series with both the transmitter and receiver.

The battery may be placed in series with the coil 1 as indicated in Fig. 1^a. A condenser 8 may then be used to prevent battery current flowing in the line. In case a permanent magnet receiver is used, the battery may be placed in effective series with the transmitter 4 only, as shown in Fig. 1^b. Fig. 2 differs from Fig. 1 in that the points of connection of receiver 5 and line 6 to the transformer are interchanged.

A substation circuit, arranged as herein set forth, has the unique advantage that when using a neutral receiver, it can be designed so as to be ideally efficient, both from an altering current standpoint and from a direct current standpoint. A neutral receiver is one which has a normally unmagnetized iron core which is magnetized by battery current in order to place it in condition for effective reception of voice currents. Neutral receivers are adapted for the arrangements illustrated in Figs. 1, 2, 1^a and 2^a. Thus, assuming as given, which is usually the case, the permissible voltage of the battery and the ampere turns necessary to properly magnetize the neutral receiver

for maximum efficiency; also assuming that the resistance of the windings 1, 2 and 3 to direct current is negligible, we may determine at once the proper direct current resistance for the neutral receiver. The characteristics of any given receiver by calculation or experiment can be determined, so that its impedance at talking frequencies can be assumed as known when its D. C. resistance has been determined. Then, also having given the set impedance, the transmitter resistance, and the energy ratio, which is the ratio of energy delivered to the transmitter to that delivered to the receiver when receiving, and furthermore, making the assumption that the transformer 1, 2 and 3 is ideally efficient, and that the impedance of the various elements to current of talking frequency acts as ohmic re-

sistance, which assumptions are sufficiently nearly true in practice, it can be shown that in such a circuit as Fig. 2:

$$5 \quad Z_s = \frac{RT(\sqrt{A} + \sqrt{B} + \sqrt{C})^2}{RA + T(\sqrt{A} + \sqrt{B})^2} \quad (1)$$

$$10 \quad y = \frac{A}{(\sqrt{A} + \sqrt{B})^2} \frac{R}{T} \quad (2)$$

$$\sqrt{\frac{B}{A}} = +\sqrt{\frac{R}{Ty}} - 1 \quad (3)$$

$$15 \quad \sqrt{\frac{C}{A}} = +\sqrt{\frac{Z_s(y+1)}{Ty}} - \left(1 + \sqrt{\frac{B}{A}}\right) \quad (4)$$

wherein,

Z_s = set impedance,

R = receiver impedance,

T = transmitter impedance,

20 y = energy ratio

$$= \frac{I_T^2 T}{I_R^2 R}$$

where I_T represents the telephonic current 25 through the transmitter in receiving I_R rep-

resents the telephonic current through the receiver in receiving, and A , B and C represent the impedances of windings 1, 2 and 3 respectively. The radicals

$$30 \quad \sqrt{\frac{B}{A}} \text{ and } \sqrt{\frac{C}{A}}$$

will therefore represent ratios between 35 number of turns. The positive values of the radicals should, in general be used.

Formula (3) follows directly from formula (2), while formula (4) is derived from 40 (1) and (2). Formulae 1 and 2 may be derived as follows:

Assume an electromotive force e in the line 6 and currents I_L , I_A , I_B , I_C , I_T , and I_R flowing in the directions indicated by the arrows in Fig. 2, and that the currents I_A , I_B and I_C all tend to produce flux in the same 45 direction. From Kirchhoff's first law, $I_C = I_L$, $I_B = I_L - I_R$, and $I_A = I_L - I_R - I_T$. Applying Kirchhoff's second law, we get: by going around the mesh containing L , R and C

$$(I) \quad e = I_L L + I_L C + (I_L - I_R) M_{BC} + (I_L - I_R - I_T) M_{AC} + I_R R \quad (a)$$

by going around the mesh containing T and A

$$(II) \quad (I_L - I_R - I_T) A + (I_L - I_R) M_{AB} + I_L M_{AC} = I_T T \quad (b)$$

by going around the mesh containing A , B and R

$$(III) \quad (I_L - I_R - I_T) A + (I_L - I_R) M_{AB} + I_L M_{AC} + (I_L - I_R) B + (I_L - I_R - I_T) M_{AB} + I_L M_{BC} = I_R R \quad (c)$$

Rearranging these equations we have, respectively:

$$I_L (L + C + M_{AC} + M_{BC}) + I_R (R - M_{AC} - M_{BC}) + I_T (-M_{AC}) = e \quad (d)$$

$$I_L (A + M_{AB} + M_{AC}) + I_R (-A - M_{AB}) + I_T (-A - T) = 0 \quad (e)$$

$$I_L (A + B + 2M_{AB} + M_{AC} + M_{BC}) + I_R (-A - B - 2M_{AB} - R) + I_T (-A - M_{AB}) = 0 \quad (f)$$

Solving the equations (d), (e) and (f) simultaneously, we get:

$$I_R = \frac{e[(A + M_{AB})(A + M_{AB} + M_{AC}) - (A + T)(A + B + 2M_{AB} + M_{AC} + M_{BC})]}{D} \quad (g)$$

$$I_L = \frac{e[(A + M_{AB})^2 - (A + T)(A + B + 2M_{AB} + R)]}{D} \quad (h)$$

$$I_T = \frac{-e[(A + M_{AB})(R - M_{AC} - M_{BC}) + M_{AC}(A + B + 2M_{AB} + R)]}{D} \quad (i)$$

In all of which we have:

$$D = [L + C + M_{AC} + M_{BC}] [(A + M_{AB})^2 - (A + T)(A + B + 2M_{AB} + R)] \\ + [A + M_{AB} + M_{AC}] [(A + M_{AB})(R - M_{AC} - M_{BC}) + M_{AC}(A + B + 2M_{AB} + R)] \\ - [A + B + 2M_{AB} + M_{AC} + M_{BC}] [(A + T)(R - M_{AC} - M_{BC}) + M_{AC}(A + M_{AB})] \quad (j)$$

Since in an ideal transformer, i. e., one which neither stores nor absorbs energy, we have no flux leakage,

Making these substitutions and simplifying, equations (g), (h) and (i), become:

$$I_R = \frac{-eT[(\sqrt{A} + \sqrt{B})^2 + \sqrt{C}(\sqrt{A} + \sqrt{B})]}{D} \quad (k)$$

$$I_L = \frac{-e[T(\sqrt{A} + \sqrt{B})^2 + AR]}{D} \quad (l)$$

$$I_T = \frac{-eR\sqrt{A}(\sqrt{A} + \sqrt{B} + \sqrt{C})}{D} \quad (m)$$

$$M_{AB} = \sqrt{AB}$$

$$M_{AC} = \sqrt{AC}$$

$$M_{BC} = \sqrt{BC}$$

Note that in obtaining equation (l), equation (h) first becomes,

$$5 \quad I_L = \frac{e(-AR - AT - BT - 2TM_{AB} - TR)}{D} \quad (n)$$

Since the transformer is assumed to be ideal, the self impedances A and B and the mutual impedance M_{AB} are of the order of

infinity, the quantity $-TR$ which is finite is 10 therefore of negligible value as compared with the first four quantities and may be dropped.

By definition

$$y = \frac{I_x^2 T}{I_r^2 R} \quad 15$$

Hence, from equations (k) and (m) we get:

$$y = \frac{e^2 R^2 A (\sqrt{A} + \sqrt{B} + \sqrt{C})^2 T}{e^2 T^2 [(\sqrt{A} + \sqrt{B} + \sqrt{C}) (\sqrt{A} + \sqrt{B})]^2 R} = \frac{AR}{(\sqrt{A} + \sqrt{B})^2 T}$$

or formula (2) above.

Assuming that $L=0$, or in other words 20 that e is the terminal voltage across the set:

$$Z_s = \frac{e}{I_L}$$

25 Then from equation (l),

$$Z_s = \frac{D}{-[T(\sqrt{A} + \sqrt{B})^2 + AR]} \quad (o)$$

Assuming an ideal transformer as above, 30 equation (j) reduces to

$$D = -RT(\sqrt{A} + \sqrt{B} + \sqrt{C})^2 \quad (p)$$

Substituting in equation (o)

$$35 \quad Z_s = \frac{-RT(\sqrt{A} + \sqrt{B} + \sqrt{C})^2}{-[T(\sqrt{A} + \sqrt{B})^2 + AR]} \quad (q)$$

which may be written as in formula (l)

40 Formulae (3) and (4) show that for any given value of y , if T and R are determined, the winding ratio

$$\sqrt{\frac{C}{A}}$$

45 may be adjusted to make Z_s any desired value. The value of y ordinarily desirable is approximately unity, which value is the condition for maximum efficiency.

If the receiver be of relatively high impedance to speech currents, the ratio

$$\sqrt{\frac{C}{A}}$$

55 will be zero or negative. By combining the formulae (3) and (4), it will be seen that the negative value will occur when $R > Z_s (y+1)$ or $R > 2Z_s$, when $y=1$. The physical embodiment of this condition is shown in 60 Fig. 1 where the receiver is connected across all three of the transformer windings and the line across 1 and 2 only. In case

$$\sqrt{\frac{C}{A}} = 0,$$

65 the turns of winding 3 become zero, of which the physical interpretation is that the line and receiver are connected at each of their

respective terminals to the same point in the transformer. The substation arrangement of Fig. 2 has been found to be of practical advantage where a substation set of unusually high total impedance is desirable, but with the highest efficiency under such circumstances. 70 75

The design formulae for Fig. 1 may be derived in a similar manner to that outlined above for Fig. 2. Assuming the reference characters to be defined as above, it can be readily shown that in such a circuit 80 as Fig. 1

$$Z_s = \frac{RT(\sqrt{A} + \sqrt{B})^2}{RA + T(\sqrt{A} + \sqrt{B} + \sqrt{C})^2} \quad (r)$$

$$\sqrt{\frac{B}{A}} = \pm \sqrt{\frac{Z_s}{T} \left(\frac{y+1}{y} \right) - 1} \quad (s)$$

$$\sqrt{\frac{C}{A}} = \pm \sqrt{\frac{R}{Ty} - \left(1 + \sqrt{\frac{B}{A}} \right)} \quad (t)$$

$$y = \frac{A}{(\sqrt{A} + \sqrt{B} + \sqrt{C})^2} \cdot \frac{R}{T} \quad (u)$$

With R , T , and y given it will be apparent that Z_s the impedance of the set may be 95 given any desired value by a proper proportioning of the three windings. One way it can be done for example is to vary the ratio of B to C , keeping B plus C constant. Under these conditions it will be seen from 100 equation (u) that $B+C$ being constant y will not vary when the ratio of B to C is changed; and from equation (r) that Z_s will change when the ratio is changed since only B occurs in the numerator while $B+C$ 105 occurs in the denominator. Z_s may therefore be adjusted without changing the energy ratio.

With these arrangements, assuming the use of a neutral receiver and a single transformer, a set can be designed to be of maximum possible theoretical efficiency with any assigned values of transmitter resistance, energy ratio and set impedance. Although reference is made herein to a neutral receiver, 110 it should be noted that the invention in its generic aspect is not limited to the use of such a receiver. Furthermore the invention is not limited to use in local battery sets. 115

Figures 1^a and 1^b typify a battery location suitable for the arrangement of Fig. 2 as well as Fig. 1. In the practical use of any set herein described, a suitable ringing generator and bell or other signaling means may be bridged across or otherwise suitably connected to the line in a manner well-known in the art, hence these features are not necessary to be described herein. A condenser 8 may be placed in the line in the usual manner as shown in Fig. 1^a in order to prevent the battery 7 sending current through the line. The coil 3 may be divided into two parts, 3' and 3'', as illustrated in Fig. 2^a. Under certain circumstances it might be desirable to ground the transformer at the electrical mid-point of its total turns, in which case 3' and 3'' would be so proportioned as to make the mid-point exactly coincide with one of the tap out points between 3'' and 1, or 1 and 2 or 2 and 3'. The total number of turns of 3' and 3'' would be equal to the turns of 3. This arrangement is the full equivalent in respect to the invention herein claimed to that of Fig. 2.

It will be noted from the form of equation (1), that the expression for the set impedance is a fraction, the numerator of which involves the product of the receiver and transmitter impedances and the denominator involves their sum. This shows that the instruments are effectively in parallel. It follows that if the set be designed so that y is approximately unity, the energy of received signals will divide substantially equally between the receiver and the transmitter.

What is claimed is:

1. A telephone circuit including three elements which consist of a line, a receiver and a transmitter, a transformer associated with said elements, said transmitter being connected across a coil of said transformer, said receiver being connected across said coil and another coil of said transformer, said line being connected across all the coils of said transformer, said coils being so wound and arranged that current passing through them from one extreme electrical terminal to the other extreme electrical terminal of said transformer produces a series aiding effect in said transformer as a whole.

2. A telephone circuit having a three coil auto-transformer and three elements consisting of a receiver, a transmitter and a line, said transformer having four tap out points, said receiver, transmitter and line each having terminals connected to said transformer at two tap out points, all of said elements having one common terminal at a tap out point and one individual terminal at a tap out point, said coils being wound so that current passing through each one in a direction away from said common terminal of

said elements has a series aiding inductive effect in said transformer as a whole.

3. A telephone circuit having a three coil auto-transformer and three elements consisting of a receiver, a transmitter and a line, said transformer having four tap out points, said receiver, transmitter and line each having terminals connected to said transformer at two tap out points, all of said elements having one common terminal and each having an individual terminal, said coils being wound so that current passing through each one in a direction away from said common terminal of said elements has a series aiding inductive effect in said transformer as a whole, the parts of said substation being so proportioned that the substation is of approximately maximum efficiency.

4. A telephone substation set comprising a transformer, a neutral receiver, a transmitter, a local battery, a series circuit including said battery, said receiver and at least a portion of said transformer, a second series circuit including said transmitter, said battery and at least a portion of said transformer, connections including at least a portion of said transformer for connecting the substation set to a line, said portions in said first and said second circuits and in said connections having a relative ratio of turns depending upon the impedances of said transmitter and said receiver to make the energy ratio (y) approximately unity in receiving signals from said line.

5. A telephone substation set comprising a transformer having three coils, a neutral receiver, a transmitter, a local battery, a series circuit including said battery, said receiver and at least one of said coils, a second series circuit including said battery, said transmitter and at least one of said coils, connections including at least two of said coils for connecting the substation set to a line, said three coils having a relative ratio of turns dependent upon the impedances of said transmitter and receiver to make the energy ratio (y) approximately unity in receiving signals from said line.

6. A telephone circuit including three elements constituting a line, a receiver and a transmitter together with a three coil auto-transformer, one of said elements being connected across one coil of said transformer, a second of said elements being connected across two coils of said transformer, and a third of said elements being connected across three coils of said transformer, said coils being so arranged that current passing through each of said coils in a direction from one extreme end of said transformer to the other extreme end thereof, produces a series aiding effect in respect to the voltage induced across said extreme ends.

7. A telephone circuit comprising a re-

ceiver, a transmitter, a line and a three coil transformer, said receiver, transmitter, and line being connected across the terminals of the coils of said transformer, said coils being so wound that in receiving the energy is approximately equally distributed between the receiver and the transmitter, the impedance of said receiver being appreciably in excess of the impedance of said transmitter.

8. An auto-transformer having three windings, and four tap out points, and three elements comprising a transmitter, a receiver, and a line, each having terminals connected to said tap out points, said connections having substantially no impedance to alternating currents, two of said elements having a common terminal.

9. An auto-transformer having three windings, and four tap out points, and three elements comprising a transmitter, a receiver and a line, each having terminals connected to said tap out points, said connections having substantially no impedance to alternating currents, two of said elements having a common terminal, said receiver and said transmitter being effectively in parallel with respect to received currents.

10. A telephone circuit comprising four elements consisting of a three coil auto-transformer, having two terminal and two intermediate tap out points, a receiver, a transmitter and a line, said three last mentioned elements each having two terminals connected to said transformer at a tap out point, three of said four elements having a common terminal, said coils being wound so that current passing through each one in a direction away from one end of the transformer terminals has a series aiding effect in said transformer as a whole.

11. A telephone circuit comprising four elements consisting of a three coil auto-transformer having two terminal and two intermediate tap out points, a receiver, a transmitter and a line, said three last mentioned elements each having two terminals connected to said transformer at a tap out point, three of said four elements having a common terminal, said transformer being so wound that the impedance of the set viewed from the line is appreciably greater than the impedance of the line.

12. A substation circuit comprising a transmitter and a receiver, connections from said instruments to a line, said instruments being connected effectively in parallel with each other with respect to signaling currents from said line, said connections comprising an autotransformer between at least one of said instruments and said line, a portion of a winding of said transformer being connected in shunt to said line with respect to said receiver.

13. A substation circuit comprising a transmitter, a receiver and a transformer for inductively coupling at least one of said instruments to a line and connections, adjusted to divide the energy of the received signaling currents approximately equally between said receiver and transmitter, for connecting said transformer, receiver and transmitter with said line in such a manner that said instruments are effectively in parallel with said line, a portion of the winding of said transformer being connected in shunt to said line with respect to said receiver.

In witness whereof I hereunto subscribe my name this 5th day of October, A. D., 1917.

KENNETH S. JOHNSON.
